Primary Examiner — Mark A Goodwin*Assistant Examiner* — Benjamin M Weeks(74) *Attorney, Agent, or Firm* — Woodard Emhardt Henry Reeves & Wagner LLP(57) **CLAIM**

The ornamental design for a lamp for the rear of a vehicle, as shown and described.

DESCRIPTION

FIG. 1 is a rear elevation view (when mounted) of the design;

FIG. 2 is a front elevation view (albeit hidden when mounted) thereof;

FIG. 3 is a plan view thereof, symmetrically showing the top and bottom plan view when mounted;

FIG. 4 is a side elevation view thereof, symmetrically showing the right and left elevation view when mounted; and,

FIG. 5 is a top perspective view thereof.

The broken lines in the figures depict portions of lamp for the rear of a vehicle that are not part of the claimed design.

1 Claim, 3 Drawing Sheets(56)
